UNITED STATES PATENT OFFICE.

JOHN H. GAULT, OF PHILADELPHIA, PENNSYLVANIA.

DESIGN FOR A DRINKING-GLASS HOLDER.

SPECIFICATION forming part of Design No. 24,962, dated December 10, 1895.

Application filed August 6, 1895. Serial No. 558,422. Term of patent 7 years.

To all whom it may concern:

Be it known that I, JOHN H. GAULT, a citizen of the United States, residing at Philadelphia, in the county of Philadelphia and State of Pennsylvania, have invented and produced a new and original Design for Goblets or Glass-Holders, of which the following is a specification, reference being had to the accompanying drawing, which shows my design in elevation.

The leading feature of my design consists in the irregular and raised surface which surrounds the top of the goblet or holder, and from which depend the irregular raised portions, which resemble stalactites in form, the handle of the goblet or holder being also provided with a similar formation, and in the annular irregular portion at the bottom thereof, which resembles stalagmites in form, each of the irregular formations referred to being so formed as to closely resemble frost or ice formations, produced by the contents of the goblet or holder overflowing and freezing.

In the drawing constituting a part of this application, A represents the goblet or glass-holder, and the goblet or holder A is provided with an irregular-scalloped upper edge, from which depend the irregular stalactite formations B, the same decreasing in size and main-

taining their irregularity from the top to the bottom.

Around the bottom of the goblet or glass-holder is a similar formation C, which, as hereinbefore stated, resembles stalagmites, and the irregular portions are directed upward and outward, and the handle D is, as will be observed, also provided with a formation which resembles that on the upper portion of the goblet or holder.

The entire design, as shown and described, presents to the eye a pleasing effect, and resembles, as hereinbefore stated, a goblet filled with water which has overflowed and frozen on the outer surface thereof.

Having fully described my new and original design, I claim and desire to secure by Letters Patent—

The design for a goblet or glass holder, as herein shown and described.

In testimony that I claim the foregoing as my invention I have signed my name, in presence of the subscribing witnesses, this 31st day of July, 1895.

JOHN H. GAULT.
